SHIELD FOR CARBIDE FEEDS IN ACETYLENE GENERATORS

Filed May 19, 1927

INVENTOR

Heribert G. Swanson

UNITED STATES PATENT OFFICE

HERBERT G. IRWIN, OF AMARILLO, TEXAS

SHIELD FOR CARBIDE FEEDS IN ACETYLENE GENERATORS

Application filed May 19, 1927. Serial No. 192,555.

This invention relates to splash valves or splash shields and drip rings adapted to prevent water splashing upon the carbide feed valve or otherwise moisture finding its way to and through the feed opening into the carbide hopper of an acetylene generator and thereby clogging the feed.

In such devices it is common to use a relatively large metallic tube depending from the 10 hopper bottom about the feed opening to a short distance above the water in the water chamber and through which tube carbide drops as it is fed from the hopper. The purpose of the tube being to shield the feed opening against moisture and water splash when the generator is hauled about. The drip ring is usually a flat band projection formed on the hopper bottom about the feed opening in place of the tube, it is used on the stationary 15 type generator and the purpose of same is to prevent water that accumulates on the under and sloping side of the hopper bottom running down into the feed opening which would soon clog the feed.

20 In recent years various types of valves have been designed for use immediately under the carbide feed in an effort to find a satisfactory means for a portable generator to prevent clogging of the feed due to moisture causing lime deposit.

25 While the metallic tube splash shield has been given extensive use, it has one drawback in that it finally clogs or closes with lime deposit at its lower end obstructing the feeding of carbide. The usual drip ring has a similar disadvantage in that powders of lime from carbide, deposit on the inner wall of the ring creating a means of capillary attraction whereby some of the water at the lower edge of the drip ring is conveyed upwardly into the feed opening thereby clogging the feed. Other splash shields such as valves, with which I am familiar give more or less trouble due to moisture and lime deposit.

The object of my invention is to provide new and useful improvements in splash shields, splash valves and drip rings for the carbide feed and carbide passageway in an 30 acetylene generator.

A further object of my invention is to overcome the usual choking up of the carbide feed due to moisture and lime deposit.

A further object of my invention is to prevent an obstructive lime deposit in a passage- 55 way for carbide.

A further object of my invention is to prevent a means of capillary attraction forming in a passageway for carbide.

A further object of my invention is to provide a splash shield and drip ring that is self cleaning.

With these and other objects in view, my invention consists in the arrangement, combination and construction of the various 65 parts of my improved device, as described in the specification, claimed in the claims, and shown in the accompanying drawings, in which:

Figure 1 is a back view of an acetylene 70 generator with walls cut away showing a sectional view of a splash shield constructed in accordance with my invention, the shield being in closed position.

Figure 2 shows my splash shield mounted 75 on a hopper bottom that may be used in such a generator shown in Fig. 1, this being an end view of the shield clamping members in open position.

Figure 3 is an end view of the shield clamp- 80 ing members in closed position.

Figure 4 is a side view of the shield and clamping members in closed position.

Figure 5 is a side view of the shield and 85 clamping members in open position.

Figure 6 shows one way for mounting my splash shield on a hopper bottom, the hopper bottom and shield being in section.

Figure 7 is a view of one of the shield 90 clamping members better illustrating details of structure.

Figure 8 is a view of another style of generator with a portion of the water chamber and carbide hopper cut away showing an 95 alternate form in which my invention may be accomplished. The splash shield here is shown in longitudinal section.

Figure 9 is a side view of the splash shield used in the generator shown in Fig. 8.

Figure 10 is a view looking down at the mouth of the water chamber of the generator shown in Fig. 8.

Figure 11 is a plan view of the outlet end of the carbide hopper of the generator shown in Fig. 8.

Figure 12 is a side view of a separable hopper bottom for a stationary generator showing my invention in a drip ring.

10 Figure 13 shows an alternate form in which my invention may be worked out in a drip ring.

Referring to the accompanying drawings, I have used the letter "A" to indicate generally the splash shield which is of hollow cylindrical form and composed of soft rubber having qualities of toughness and durability. When greater strength is required in a shield it may contain one or two plies 15 of cord or preferably a knitting of seamless tubular form. The shield having plain ends shown in Fig. 9, may be cut to the required length from rubber tube stock. Certain 20 grades of extra heavy inner tube stock such as used in motor vehicle tires have been found to serve satisfactorily for the purpose. The shields having beaded lower end portions shown in Figs. 1, 2, 3, 4, 5 and 6 are preferably 25 formed of suitable rubber gum heat treated or cured in molds under pressure as is well known in the art of rubber article 30 and motor vehicle tire manufacture.

Referring to Fig. 1, numeral 1, designates the water chamber of an acetylene generator; 35 2, the carbide hopper; 3, a separable hopper bottom carrying a rim gasket 5 and clamped between the hopper and water chamber. A band ring 6, of such size as will receive the upper end of the splash shield is formed in- 40 tegral with the hopper bottom about the carbide feed opening 7, to provide an annular shoulder by which the upper end of the splash shield may be secured to the hopper bottom with a band clamp 8, see Fig. 6. The 45 shield should be of sufficient length to extend downward to a short distance above the water level. Ordinarily this would constitute a satisfactory shield against moisture from the hopper bottom and the splashing 50 of water in a generator for limited portable use, such as hauling the generator on a hand truck in and about the shop. But when the generator is to be mounted on a motor vehicle for extended service outside the shop 55 and when it is desirable to haul the generator fully charged with water, carbide and gas, a manually operated clamping device is pro- 60 vided to clamp and close the shield immedi- ately under the carbide feed valve 9, thus preventing water reaching the feed valve and carbide outlet 7. This form of clamping de- 65 vice has a square frame consisting of a pair of relatively long stud bolts 10, forming two opposite sides and a pair of tube members 10E, forming the other two opposite sides of

the frame. The stud bolts are welded at their midway portion 10C, (Fig. 2) to the hopper bottom near the ring 6 and at dia- 70 metrically opposite sides of the hopper bot- tom. Eye projections 10H, formed in line on the side of the tubes near the ends there- 75 of slip over the threaded ends of the studs and with the nuts 10J, the tube members are clamped in place. The clamping bars 11, and 12, consists of suitable lengths of round bar stock extending through the tube mem- 80 bers of the frame and bent to form rectangular frame like structures having end portions 11K, and 12K. The abutting ends of the bar stock after the bending is complete may be welded to make an endless structure add- 85 ing rigidity. The upper sides of the clamp- 90 ing bars pivot in the tube members 10E and the lower exposed sides 11 and 12 engage the splash shield. The end portions of the bars should be of such length that when the side portion of the bars are moved toward each other they will meet immediately and direct- 95 ly under the carbide outlet 7 so that in clos- 100 ing the shield the pocket made thereby will hold not more than a mere handful of carbide. By clamping the shield directly under the carbide outlet the bending of the wall of the shield will be about equal on opposite sides and the clamping bars may each have an equal movement. Also the side portions 105 11 and 12 should swing in parallelism so as to clamp the shield with equal tension along the line of engagement. Furthermore the 110 clamping bars should be connected so that when one is moved back and forth as from open position to clamping position and back again the other bar will move likewise. And in addition to moving back and forth simultaneously the clamping bars should be pro- 115 vided with means whereby they will remain under spring tension in either open or closed position. This may be accomplished by add- 120 ing the fingers 11N, and 12N, and the spiral compression spring 13, to one or both end portions of the clamping bars. Upon refer- 125 ence to Fig. 2 it will be seen that these fingers extend between the end portions 11K and 12K overlapping a short distance. The finger 11N is made integral with the end portion 11K about midway thereof and about right angles thereto, so that when the bar 11 is in open position the finger will range in a direction above center of the side portion 12K to a point midway between the two end 130 portions of the clamping bars. The project- 135 ing end of this finger terminates in an elongated eye cam piece 11Q. The finger 12N, is made integral with the clamping bar 12 at the upper pivot end of the end portion 12K and the finger inclines downward to- 140 ward the center of the opposite end portion 11K, passing through the eye cam-piece 11Q and overlapping the finger 11N a short dis- 145 tance. The overlapping of the fingers serve 150

as a stop limiting the opening movement of the clamping bars. The spring 13 fits loosely about the finger 12N whereupon one end seats at the junction of the finger with the 5 end portion 12K of the bar, while the opposite end of the spring presses constantly against the cam-piece 11Q. A plain washer may be used between the end of the spring and the cam-piece as a necessary wearing 10 medium directly engaging the cam. It will be seen that upon moving the clamping bar 11 to closed position the extremity of the finger 11N moves upward carrying its cam-piece 11Q upward to a point above a straight 15 line running through the center of the pivots 10E, which position the cam-piece may be referred to as being above center. By reason the finger 12N extending through the eye of the cam-piece the extremity of same is 20 carried upward also above center thus moving the clamping bar 12 to closed position simultaneously with the bar 11. The pressure of the spring 13 on the lower side of the cam-piece in position above center is applied 25 to the clamping bars through the medium of the fingers 11N, 12N and pivots 10E, thus holding the clamping bars in closed position, clamping and closing the shield "A" as shown in Figs. 1, 3 and 4. By moving 30 the clamping bar 11 to open position, (see Fig. 2) the fingers and cam-piece are brought downward to a position below center, which position the pressure of the spring applies to push the clamping bars apart. In less 35 words, the fingers 11N, 12N, cam-piece 11Q and spring 13 may be described as means for gearing the clamping bars 11 and 12 together, reversing the pressure of the spring upon the pivots of the bars for holding same 40 in either open or closed position. The side contact of the fingers as will be seen in Fig. 2 serve to stop the clamping bars in open position. An eye 15 is provided on the lower end of the portion 11K of clamping bar 11 45 for connection with a crank 17 through the medium of the link 16, see Fig. 1. The crank 17 is secured to the inner end of a rock shaft 18, which latter extends outward of the wall of the water chamber 1 through a suitable 50 tubular bearing and packing gland not shown. The outer end of the rock shaft terminates in an upright handle 19, by which the operator may move the shield clamping bars to either open or closed position at will. 55 As a safety means to prevent undue gas pressure on wall of the shield above the clamping bars in case the operator fails to open the clamping bars before releasing gas pressure in the water chamber, as when refilling 60 the generator, a small recess "N" is made in the bar 11 or the bar 12 or in registration in both bars midway between their end portions on the side engaging the shield, see Fig. 7. With this recess in the bars the shield 65 is not clamped tightly at the point of recess

thus providing a passageway between the walls of the shield by which gas from the carbide hopper may escape into the water chamber.

It will be understood that lime from calcium carbide, although a water tightening element, particularly when first formed, does not cake to any appreciable degree of thickness on the wall of a passageway for carbide whose surface is changing at intervals. By 70 reason of the elastic wall of the splash shield it is changed in contour near the carbide outlet at intervals through the use of the clamping means which, would shed any appreciable deposit thereon in that vicinity. Besides the 75 clamping means, the dashing of water upon the shield as when the generator is hauled in a motor vehicle often changes the contour of the entire shield for a short period of time thus breaking loose any lime cake formed on 80 the inner surface of the shield in use between hauls. Furthermore, due to the elastic wall of the shield, the wall is pressed and thereby reduced in thickness throughout its length 85 when there is gas pressure in the generator. Upon releasing gas pressure as when refilling the generator the wall of the shield returns to normal thickness which would loosen any 90 lime cake formed on the inner surface thereof between fillings. Thus it will be seen that the inner surface of the splash shield is changed 95 in various ways through the use of the generator and is therefore self cleaning.

Referring to Fig. 8, numeral 1 designates 100 the water chamber of an acetylene generator; 2, the carbide hopper; 3G, the hopper bottom which in this style of generator is made integral with the carbide hopper; 7B, the carbide feed valve; "A", the splash shield 105 which in this generator has plain ends, being cut the desired length from soft rubber tube stock. The upper end of the water chamber terminates in a short cylindrical mouth-piece 1C, having comparatively thick side walls and a smooth and rounded upper edge or 110 rim. Through this mouthpiece the splash shield extends downwardly into the water chamber to a short distance above the water level. The upper end of the shield being stretched outwardly over the rim and downward upon the outer side of the mouth-piece 115 whereupon it contracts when released, holding itself in place. The lower end of the carbide hopper terminates in a short tube 21, having an outside diameter of such size as 120 will fit into the end of the shield. A second short tube 22, whose inside diameter is of such size as will receive the mouth-piece with the shield in place, is made integral with the carbide hopper about the tube 21 thus forming 125 a deep annular channel 2H, into which the mouth-piece with the shield thereon extends when the hopper is in place. The rubber ring 2J, at the bottom of the channel 130 serves as a gasket for sealing against escape-

ment of gas at the rim of the mouth-piece. Stud bolts 1H, extending upright from the water chamber through eye projections 2X, on the hopper extension 22 serve with the nuts 5 1Y, for clamping the carbide hopper onto the water chamber. The splash shield in this generator is without clamping means on account of the generator not being intended for extensive portable use. In hauling this generator on a hand truck in and about the shop there is occasionally some splashing of water upon the outer wall of the shield, mostly upon the lower end which, would cause some agitation in the wall of the shield. And if the 10 generator be tilted to the side as in hauling it over irregular surfaces the wall of the shield would be changed in contour for a short period of time by gravity, thus sheathing lime deposit which may have formed on the inner surface of the shield. When there is as much as five pounds variation in gas pressure in the generator there is a slight variation in thickness of the wall of the shield which goes to prevent the caking of lime on 15 the inner surface thereof.

Referring to Fig. 12, numeral 3 designates a separable hopper bottom which may be used in a stationary generator of a style similar to that shown in Fig. 1. The drip ring 20 "AB", is the same as the splash shield except it is shorter and may be secured to the hopper bottom the same as the splash shield shown in Fig. 6. And it may be cut to the desired length from suitable rubber tube stock. This 25 drip ring prevents the formation of lime cake on the inner surface thereof by changing in wall thickness due to variation in gas pressure in the generator, as for an instance, when the pressure is released to refill with water and carbide.

Referring to Fig. 13, the drip ring "AC", 30 consists of a suitable length of soft rubber tube stock having a margin adjacent its ends cemented, then the tube is doubled back upon 35 itself bringing the cemented ends together to be heat treated. The space "X", between the two walls of the ring may be filled with an elastic material such as air, soft rubber strands, a coil of small soft rubber tubing 40 or rubber sponge material, not shown, the filler being inserted before the cemented marginal ends of the casing are cured together. The vulcanized end "Y", of the drip ring thus formed may be clamped on to the 45 hopper bottom in a manner similar to that shown in Figs. 6 and 12. This cushion drip ring, as it might be called, has some advantage over the plain ring in that it has greater contraction under gas pressure and therefore 50 greater expansion upon releasing gas pressure. Thus the resistance against lime caking on the walls of the ring is greater. This 55 form of my invention may be used in generators having the major portion of the carbide hopper extending down into the water 60 65

chamber. Such hoppers have more exposed surface which condenses more moisture, consequently there is more drip at the drip ring.

It will be seen that by preventing lime deposit on the inner surface of the shield also 70 prevents moisture being drawn up into the shield or drip ring and into the carbide feed outlet by capillary attraction through the pores of the deposit.

While I have shown and described a variety of splash shields and drip rings constructed in accordance with my invention, it will be manifest to persons skilled in the art that many changes may be made in minor detail of structure in adapting the device to various use, and slight changes in the mode of operation of same within the scope of the appended claims, without departing from the spirit of the invention; it is, therefore, to be understood that this invention is not to be 85 limited to the details described and shown.

What I claim is:—

1. In a valve shield for the valve controlled carbide feed outlet of a carbide feed hopper mounted on the water chamber of 90 an acetylene generator, a flexible tube dependent from about said outlet, means for clamping said tube laterally and closing it adjacent to said outlet.

2. A tubular carbide feed shield having an 95 inner wall impervious to acetylene and water moisture under generator pressure and inherently unstable in wall thickness and wall surface at substantial variation in generator pressure, an outer wall, and an enclosed cavity 100 between the walls.

3. In an acetylene generator having a water chamber and a carbide feed hopper with a valve controlled carbide feed outlet mounted on the water chamber, a vertically disposed 105 tubular shield dependent from about the carbide feed outlet, said shield having an inner and an outer circumferential wall impervious to acetylene and water moisture under generator pressure forming a sealed annular enclosure, elastic material in said enclosure, the inner wall of the shield being elastic to be expanded and compressed with said enclosed elastic material by gas pressure in the generator and to return to normal size 110 and thickness when gas pressure in the generator is released, provided to prevent the formation of carbide residue deposit on the inner surface of the shield and consequent capillary attraction conveying water moisture from the rim of the shield upward into the shield and carbide feed outlet.

4. In a valve splash shield for the valve controlled carbide feed outlet of a carbide feed hopper mounted on the water chamber of an acetylene generator, an annular shoulder about said carbide feed outlet, a detachable member consisting of a tube of flexible material impervious to water moisture under generator pressure dependent from said an- 125 130

nnular shoulder and extending a substantial distance downwardly into the generator chamber, including annular elastic means constantly tending to retain the valve member 5 cylindrical, and annular clamping means for securing the valve member onto said shoulder.

5. In a portable acetylene generator having a water chamber and a carbide feed hopper with a valve controlled carbide feed outlet 10 let mounted on the water chamber, a valve splash shield for the carbide feed outlet designed to be closed when the generator is hauled about, adapted to prevent water splashing into said carbide feed outlet and 15 also to prevent water running into the carbide container through said outlet should the generator be accidentally overturned in hauling, consisting of a vertically disposed tube of resilient material dependent from about said 20 carbide feed outlet and extending a substantial distance downwardly into the generator chamber, and means for gripping and closing the tube immediately under the carbide feed outlet, said gripping means being manually operated to grip and release said tube 25 through the medium of a connection with a rock shaft terminating in a handle on the exterior of the generator.

6. In a portable acetylene generator having 30 a water chamber and a carbide feed hopper with a valve controlled carbide feed outlet, a vertically disposed tubular splash shield dependent from about the carbide feed outlet and extending downward into the water 35 chamber of the generator, said shield having an elastic and flexible wall impervious to water moisture under generator pressure.

7. In a portable acetylene generator, a tubular carbide feed passageway of elastic 40 material impervious to water moisture under generator pressure extending from about the carbide feed outlet downward into the water chamber, said passageway designed to protect the carbide feed outlet from splashed 45 water in the chamber, the lower edge of said passageway being free to swing laterally upon tilting the generator.

8. A generator comprising a container, a hopper mounted in the upper end of the container and provided with a depending apron, a flexible skirt connected to the apron and depending therefrom and having the free end thereof freely movable in the container to prevent liquid in the container from splashing 55 into the hopper, the bottom of the hopper having a discharge opening embraced by the skirt, a valve for closing said opening.

HERBERT G. IRWIN.
